FOOD AND BEVERAGE DISPENSER

Billy J. Rogers, Central National Bank Bldg.,
Houston, Tex. 77002

Filed Apr. 3, 1968, Ser. No. 11,286

Term of patent 14 years

Int. Cl. D12—13

U.S. Cl. D14—3

I claim:

The ornamental design for a food and beverage dispenser, as shown and described.
